UNITED STATES PATENT OFFICE

WILBUR L. WRIGHT, OF FULTON, AND JOSEPH T. BOND, OF PHOENIX, NEW YORK,
ASSIGNORS TO OSWEGO FALLS CORPORATION, OF FULTON, NEW YORK, A COR-
PORATION OF NEW YORK

PAPER CONTAINER

Application filed February 15, 1927. Serial No. 168,333.

The purpose of this invention is to successfully solve the difficult problem of providing a tapered or nesting paper container that embodies a removable slip cover, that will comply with the requirements of the public and trade, that will be capable of manufacture by quantity production methods, and that can be placed on the market at a reasonable price.

With the foregoing and other objects in view, the invention consists in certain novel structural features, and/or in formations and combinations as more fully and particularly set forth and specified hereinafter.

Referring to the accompanying drawings, forming a part hereof:

Fig. 1 shows the upper or large diameter end portion of a nesting or tapered paper container of our invention, in sectional elevation.

Fig. 2 shows the tapered paper container of Fig. 1 in sectional elevation, the cover not being shown.

Fig. 3 shows in longitudinal section, part of a hollow mandrel and part of a tapered paper body or barrel located in such mandrel with its large extended end projected upwardly therefrom, preparatory to shaping such end to form the peculiar novel container body rim.

Fig. 4 shows in longitudinal section, the structures of Fig. 3, and the upsetting or forming head, and the rim of the paper container body as formed by the cooperation of the mandrel and head.

In the drawings, we show a paper container that embodies a tapered or nesting sheet paper body or barrel 1; a suitable bottom that includes bottom closing disk 2, indicated by dotted lines, Fig. 2; and a removable slip friction cap or cover 3, formed of sheet paper material.

The barrel 1, is tapered to its large mouth, and is preferably composed of a sheet of suitable paper board or like sheet fibrous material usually formed by folding a flat sheet paper blank around a mandrel so that its ends overlap and can be cemented or otherwise secured together to form a liquid tight joint that extends longitudinally throughout the length of the hollow body or barrel thus formed. This barrel tapers or increases in

diameter from its lower to its large mouth or open end to produce a truncated cone shape. These containers having tapered bodies when without their covers, can be nested one within the other into stacks, for packing and shipping purposes, where economy in bulk or space is desirable, the covers for the containers being suitably assembled for packaging with the container bodies, if desirable. The lower or small diameter end of the body is closed to, preferably, form a liquid tight joint and an annular depending base or rim 2^a, by a suitable bottom closure that preferably embodies a heavy flat inset paper board bottom disk 2, of overlarge diameter, and suitable body formation and crimping, upsetting or rolling tightly and permanently securing said bottom disk and forming said annular base 2^a. However, our present invention is not concerned with the particular bottom formation.

The sheet material barrel 1, is originally formed of substantial over length both at its small (lower) end and at its large (upper) end 1^a, to provide an extra body length to be taken up by the bottoming process and to form the annular projecting base 2^a, and an extra top body length to be taken up by the peculiar top exterior cover-receiving rim formation.

The upper large end of the body is formed with an annular exterior more or less elastic rim-forming hollow roll or crimp that is radially flattened or narrow and that is longitudinally or vertically elongated and that forms and constitutes the transversely or radially rounded annular top edge or lip 4, of the container surrounding its mouth, and that provides the exterior vertical approximately cylindrical wall 4^b, in downward exterior continuation of the lip 4, and which wall is cushioned or more or less elastic or yielding for frictional-holding sliding contact with the cover flange.

The exterior depending substantially vertical and cylindrical wall 4^b, terminates in the bottom inwardly radially or transversely rounded or curved lower end portion 4^a, of the rim forming roll, and this inturned portion 4^a, terminates in the free in, or if so desired

up, turned free edge 4^c, that abuts the tapered outer surface of the barrel 1, with the raw edge extremity preferably covered and concealed. The bottom edge 4^c, of the roll bears 5 against but is preferably not secured or fastened to the tapered outer surface of the barrel 1, and hence is free to yield and slightly move with respect to the barrel during the operations of applying and removing the cover.

10 The vertically elongated vertical rim forming roll, in connection with the outer surface of the barrel 1, within the roll, encloses or forms an annular air cushion, pocket or chamber 4^d, which aids in expanding the more or less elastic roll in maintaining its friction grip on or engagement with the cover flange.

15 This rim-forming roll formation is at the exterior of the barrel and permits the flaring inner surface of the barrel to continue unbroken and at a uniform angle from the bottom formation to the rounded top edge or lip 4, of the barrel, which is a desirable characteristic.

20 25 The paper material cover 3, is of any desirable or suitable formation of the slip cover type with a container mouth-covering top wall and an annular substantially vertical cylindrical depending flange 3^a, that is vertically or longitudinally elongated with respect to the vertical length of the rim-forming roll of the container body, which flange is stiff and with a cylindrical inner surface without projections, i. e. smooth-surfaced.

30 35 This cover 3, is preferably so formed that when the slip cover is in normal closing position on the body to constitute therewith the complete container, the usually flat top wall of the cover closes down on and abuts the annular top edge or lip 4, of the body, and the

40 45 cover flange 3^a depends to a distance below the rim-forming exterior roll of the body, and at its inner surface has more or less tight frictional holding engagement with the elongated vertical cylindrical outer wall 4^b, of said rim. The internal diameter of the long cylindrical cover flange 3^a, more or less closely approximates the normal external diameter of the elastic elongated cylindrical rim

50 55 wall 4^b, and the cover can be slipped to and from container body covering position by exercise of the necessary power to overcome the friction between the engaging cover and rim surfaces even though said friction is augmented by the elasticity of said friction wall which compensates for slight variations in the internal diameter of the cover flange and distortions thereof from accurate cylindrical form. Furthermore, the vertically

60 65 elongated form of the outer wall 4^b, of the rim, aided if need be by its elasticity and trapped air backing, affords ample area of gripping frictional contacting surfaces between said wall and the long cover flange to maintain the cover in closing position on the

body to meet trade and user's requirements.

The wide exterior annular top lip 4, that is radially rounded and curves upwardly, outwardly and downwardly to merge into the vertical outer wall 4^b, materially aids in the initial movement of starting the cover onto the container which is usually accomplished by a tilting movement of the cover onto the body top.

70 75 The tapered container body is originally formed with the overlong large tapered end 1^a, for formation into the exterior rim-forming roll, preferably by means of a hollow mandrel 5, and a roll forming die or crimping head 6. The paper body, or at least said overlong end 1^a, thereof is first preferably more or less heavily paraffined or otherwise provided with a lubricating waterproofing material, to afford lubrication between the contacting rubbing surfaces of the paper and die during the upsetting and rolling operation to prevent fracture and breaking of the paper and to permit reshaping and expanding of the paper to a new permanent form without opening fissures and separations in 80 the paper. The body 1, is then inserted in the hollow mandrel 5, say as indicated by Fig. 3. The die 6, having in its bottom face peculiarly formed and proportioned crimping or upsetting groove 6^a, then descends on 85 the overlong paper body end 1^a, and in co-operation with the end die face 5^a, of the mandrel, reduces the overlong body end, to the desired permanent rim-forging roll form substantially as shown by Fig. 4.

90 95 As at present advised by experience, we do not wish to limit all features of our invention to such method or such apparatus for the formation of our new nesting container body rim formation.

100 105 What we claim is:—

110 115 1. A nesting paper container comprising a stiff stable longitudinally tapered body at its large upper end or mouth formed with an exterior rim-forming hollow roll longitudinally elongated and radially flattened and inturned at its annular lower end to contact the exterior surface of the tapered body, said roll providing an exterior longitudinally elongated annular wall for frictional sliding holding contact with the depending cylindrical flange of a slip cover, said body having a top annular transversely curved top lip surrounding the mouth of the body and continuing from the tapered inner longitudinal surface 120 to said exterior wall of said rim.

125 130 2. A container comprising a sheet paper body longitudinally tapered for nesting, from its bottomed small end to its upper large mouth end, said body formed with an annular exterior rim-forming roll surrounding its mouth and providing said body with a transversely rounded top lip surrounding said mouth and an annular approximately cylindrical vertically elongated flexible wall de-

pending from said lip and of enlarged diameter with respect to and spaced outwardly from the tapered upper end of the body and at the bottom terminating in an annular in-turned edge portion for contacting the tapered body to provide an annular cushioning air pocket backing said wall.

3. A container comprising a self-supporting stable paper material body tapered for nesting, the large mouth end of said body formed with an exterior annular depending rim forming roll that provides an exterior depending vertically-elongated cover-flange gripping and contacting wall having its lower end annularly contracted to contact the body wall, in combination with a slip cover for said mouth end of the body having a depending annular flange the minimum internal diameter of which is approximately equal to the external diameter of said wall.

4. A paper container comprising a bottomed body, in combination with an annularly flanged friction slip cover for the mouth end of said body, said body longitudinally tapered to its large mouth end and there formed with an exterior annular depending rim providing an internal annular trapped air pocket surrounding the tapered wall of the body and having an exterior approximately cylindrical elastic wall fitting within the cover flange with a sliding friction gripping cover holding contact, the lower end of said wall turned in and contacting said body.

5. A container comprising a tapered bottomed body longitudinally tapered internally to the rounded top lip surrounding its large mouth, in combination with a removable slip cover for said mouth with an annular depending approximately cylindrical strong stiff flange exteriorly surrounding said mouth end of the body, said mouth end of the body having an exterior approximately cylindrical elastic wall depending from said top lip and of greater diameter than the maximum external diameter of and surrounding the tapered mouth end of the body and of shorter vertical length than said cover flange and formed to fit therein with a friction gripping cover holding sliding contact, the annular lower end of said wall contacting the exterior surface of the tapered body.

6. A container having a sheet paper material body longitudinally tapered for nesting, the large tapered end portion of the body rounded upwardly and outwardly and turned downwardly and inwardly to form a permanent exterior annular depending approximately cylindrical elastic wall to fit within the annular depending approximately cylindrical flange of a removable slip cover for the large end of the body with a friction gripping cover holding sliding contact, the lower end of said wall contacting said tapered body to trap air between the wall and body.

Signed at Fulton, county of Oswego, State of New York, this 11th day of February, 1927.
